UNITED STATES PATENT OFFICE.

LEROY HALL ROBY AND GILES CARL ROBY, OF FOSTORIA, OHIO.

CONVERTIBLE PIANO STOOL AND CHAIR.

SPECIFICATION forming part of Letters Patent No. 602,773, dated April 19, 1898.

Application filed September 20, 1897. Serial No. 652,307. (No model.)

To all whom it may concern:

Be it known that we, LEROY HALL ROBY and GILES CARL ROBY, citizens of the United States, residing at Fostoria, in the county of Seneca and State of Ohio, have invented a new and useful Convertible Piano Stool and Chair, of which the following is a specification.

Our invention relates to improvements in convertible piano stools and chairs; and the object that we have in view is to provide a structure in which the elements may be adjusted to form a chair to be used by a person performing at a piano or as a stool to accommodate two persons playing a duet at a piano.

A further object of the invention is to provide an adjustable seat which may be raised to accommodate persons of different heights, said vertically-adjustable seat being held or locked securely in either its raised or lowered position.

A further object of the invention is to provide improved means for raising or lowering the seat-frame without rotating the same and incurring the liability of striking and injuring the piano.

A further object of the invention is to improve the convertible stool and chair in minor details with a view to simplifying its construction, promoting ease and facility of adjustment, and making it strong and durable in service.

With these ends in view the first part of our invention consists in the combination, with a base and a standard, of a sectional seat-frame, the base member of which is rotatably mounted on the standard, while the other member of said seat-frame is slidable horizontally on the base member for the purpose of making the seat-frame extensible longitudinally, a back connected to the slidable member of the seat-frame and adapted to be raised or lowered to occupy positions either at right angles to the seat-frame or in substantially the same horizontal plane therewith, and means for holding the slidable member of the seat-frame and the adjustable back rigidly in either of their adjusted positions; and the invention further consists in the novel combination of elements and in the construction and arrangement of parts, which will be hereinafter more fully described and claimed.

To enable others to understand our invention, we have illustrated the preferred embodiment thereof in the accompanying drawings, forming a part of this specification, and in which—

Figure 1 is a perspective view showing our invention adjusted for service as a chair. Fig. 2 is a vertical central sectional view of the chair and stool in the position shown by Fig. 1. Fig. 3 is a similar sectional view with the structure adjusted to form a stool on which two persons may sit when playing on the piano. Fig. 4 is a sectional plan view on the plane indicated by the dotted line 4-4 of Fig. 2. Fig. 5 is a horizontal sectional view on the plane indicated by the dotted line 5-5 of Fig. 2. Fig. 6 is a horizontal sectional view through the vertically-adjustable seat on the plane indicated by the dotted line 6-6 of Fig. 3, looking in the direction indicated by the arrow. Fig. 7 is a detail view of the links which connect the adjustable back with the sliding section of the seat-frame. Fig. 8 is a detail perspective view of one of the slotted plates attached to the seat for the seat-lock to engage therewith. Fig. 9 is a vertical transverse view on the plane indicated by the dotted line 9-9 to show the locking device for holding the members of the seat-frame in fixed position in relation one with the other.

Like numerals of reference denote like and corresponding parts in each of the several figures of the drawings.

Referring by numeral to the drawings, 1 designates a base having the diverging legs 2, a vertical socket 3, and the reinforcement-plate 3^a. This socket is of angular form in cross-section and it is closed at its lower end by a rigid or integral head 4, said head forming a seat for the coiled lifting-spring 5, which is loosely fitted in the angular socket of the base.

6 is a vertically-adjustable standard fitting snugly in the angular socket of the base. This standard is substantially square in cross-section to conform to the cross-sectional contour of the socket, in order that the standard may fit in the socket and be kept from rotating in a horizontal plane therein; but at the same time the standard is free to slide vertically in the socket to sustain the seat at the desired elevation. This vertically-adjust-

able and non-rotatable standard is arranged to rest or seat itself upon the coiled lifting-spring 5, the latter having a tendency to normally raise the standard and the seat-support thereon; but the tendency of the lifting-spring is overcome by means of the locking-pawls 8, which are controlled by the levers 9, operatively connected to an adjusting-ratchet 10.

The angular standard is provided in two opposite faces with longitudinal channels 11, that extend, practically, from the lower to the upper ends of the standard, and the other two faces of the angular standard are provided with the short longitudinal channels 12. In the short longitudinal channels are fitted the locking-pawls 8. Each locking-pawl consists of a plate, which is pivotally attached at its upper end to the standard by bolts or pins 8^a, so that the upper ends of the pawls are practically flush with the faces of the standard. The lower ends of the pawls have teeth or serrations 8^b formed thereon, and against these lower toothed ends of the pawls bear the pressure-springs 13, which are fitted and housed within sockets 13^a, provided in the standard near the lower end thereof. These springs normally press the lower serrated ends of the pivoted pawls outwardly beyond the faces of the standard; but the pawls may be retracted by the levers 9 and the adjusting-ratchet 10, so that the lower serrated faces of the pawls may lie practically flush with the standard and permit the latter to be raised or lowered by hand vertically within the socket of the base. Said pawls are provided with angular arms 14, that fit around the corners or angles of the standard and are housed within transverse channels or grooves 11^a in the standard. The levers 9 are arranged longitudinally within the long channels 11 in the standard, and each lever is fulcrumed at a point intermediate of its length on a pin or screw 9^a, which is fastened in the standard. The lower ends of the levers are attached pivotally to the angular arms 14 of the pawls, as at 14^a, and the upper ends of said levers are pivotally attached to the adjusting-ratchet 10 by providing tenons on said upper ends of the levers, which tenons pass through apertures in the adjusting-ratchet at diametrically opposite points therein. This adjusting-ratchet fits loosely around the upper end of the standard 6, and said ratchet has a transverse web 10^a, which is integral with the ratchet. This transverse web of the ratchet passes through a notch or recess 6^a, formed in the upper extremity of the standard, and in said web is formed a central aperture, through which passes a vertical spindle 15. This spindle extends longitudinally through a central bore or passage 15^a, provided in the standard 6, and on the lower end of said spindle is fitted a washer 17 and a nut 18, the latter being screwed on the threaded lower extremity of the spindle to clamp the spindle rigidly within the standard. The upper part of this spindle passes through the

aperture provided with the web 10^a of the adjusting-ratchet, and it is extended through a casting 19 and a pivot-block 20, provided in the base-section of the sectional seat-frame. The casting 19 is constructed for attachment to the upper end of the standard 6 and to serve as a support for the seat-frame to enable the latter to rotate freely in a horizontal plane on the standard. This casting consists of a clip 19^a and a head-plate 19^b. The head-plate is disposed in the horizontal position, while the clip depends from the lower side of the head-plate. This clip embraces opposite sides of the standard at the upper end thereof, and it is fastened rigidly to the standard by screws or any other suitable fastening means. The head-plate 19^b of the casting fits closely against the lower side of the seat-frame, and upon this head-plate bears the pivot-block 20, which is attached to the seat-frame and forms a metallic bearing for the upper extremity of the spindle 15.

The adjusting-ratchet 10 fits compactly with relation to the head-plate of the casting 19, and said ratchet is provided with a series of radial notches forming a plurality of teeth, with which may be engaged a prong 22 of an adjusting-lever 21. This adjusting-lever is curved or bent, substantially as shown by Fig. 4 of the drawings, and said lever is fulcrumed at a point intermediate of its length, as at 23, on the central bridge-bar of the base member forming a part of the seat-frame. The prong 22 of the adjusting-lever depends from the lower side of the seat-frame, and it lies close to the radially notched or toothed edge of the adjusting-ratchet, so that when the lever is turned in a horizontal direction the prong 22 will engage with one of the notches or teeth of the adjusting-ratchet for the purpose of turning the latter a sufficient distance to move the levers 9 and retract the locking-pawls 8 within the channeled standard.

One end of the adjusting-lever 21 is provided with a handpiece, as shown, arranged to extend from one side of the seat-frame, and this handle of the lever works in a keeper 24, fastened to the lower side of the seat-frame, near one edge thereof, to hold the lever in proper relation and permit it to have the necessary horizontal movement to throw its prong 22 into and out of engagement with the adjusting-ratchet, and to this adjusting-lever is connected a retracting-spring 25, one end of which is attached to the seat-frame and the other end to the adjusting-lever, so as to hold the latter in position for its prong 22 to clear the adjusting-ratchet.

The standard 6 is adjusted in the socket of the base to have its holding-pawls 8 lie opposite to serrated or toothed plates 26. The serrated plates are countersunk in suitable channels or grooves provided within the socket of the base, and they are fastened in place by a suitable device, so that the serrated faces of the plates are substantially flush with the walls of the sockets and are exposed for the

serrated ends of the pawls 8 to engage therewith when the said pawls have their free ends forced or projected outwardly by the tension of their pressure-springs.

5 From the foregoing description it will be apparent that the standard may be held in a locked position at any desired elevation by the pawls 8 engaging with the serrated plates 26 in the socket of the base. The standard is 10 adjustable vertically within the base without rotating the standard therein; but before the standard can be raised or lowered the adjusting-lever 21 must be moved to turn the adjusting-ratchet 10 a limited distance sufficient 15 to move the levers 9 and retract the pawls 8, whereby the pawls are free from engagement with the serrated plates 26, and the standard may be raised or lowered vertically within the base. When the adjusting-lever 21 is released, it is retracted by its spring 25 to release its prong 22 from the adjusting-ratchet, and the pawls are thus freed from restraint by the levers 9, so that the springs 13 force the pawls outwardly and permit the serrated 25 ends of the pawls to engage with the serrated plates and hold the standard rigidly in place. The seat-frame is adjustable vertically with the standard; but this seat-frame is also capable of a free turning movement in a horizontal plane by reason of the seat-frame resting upon the head-plate of the casting 19 and having its pivot-block 20 loosely fitted to the upper extremity of the vertical spindle 15.

30 designates the seat-frame. It consists 35 of a base member 31 and a slidable member 32. The slidable member is arranged to fit loosely within and upon the base member, so as to move horizontally and longitudinally therein to make the seat-frame extensible. 40 The seat-frame has its base member constructed with a central bridge-bar 33, the ends of which are united rigidly to end bars of the base member 31, and which bridge-bar forms a support for the cross-bars of the slidable 45 member 32. The back of the chair is indicated at 34, and this back is provided with short posts 35, which are hinged or pivotally attached at 36 to the rear rail of the slidable member 32 of the seat-frame. This hinged 50 back is adjustably attached to the slidable member of the seat-frame for the purpose of lowering the back when the slidable member 32 is extended lengthwise of the seat-frame; but when the back is raised to an upright position the slidable member of the seat-frame 55 is retracted in the base member thereof. When the back is raised and the slidable member of the seat-frame retracted, the structure forms a chair with a back to support the 60 operator; but when the back is lowered and the slidable member of the seat-frame extended to project the same beyond the base member the structure is converted into a stool with two seats, one of which is formed by the back 65 34 and the other of which is carried by the slidable member of the seat-frame. This adjustment of the back and slidable seat mem-

ber is effected simultaneously by means of the links 37. These links are curved throughout their length to enable the front ends 70 thereof to be attached to the slidable member of the seat-frame, while the other ends of the links are loosely attached to the rear side of the hinged back 34. The links pass loosely through slots in angular brackets 31^b, 75 which are fastened rigidly to the back rail of the base member 31 of the seat-frame. As shown by the drawings, we prefer to make these links from a single rod or bar of metal, which is bent at its middle to form the pintle-bar 38 and afterward bent to form the parallel links, said links being curved, as described and as illustrated by the drawings. The pintle-bar 38 of the links is loosely fitted 80 in a loop or keeper 39, fastened to the rear 85 rail of the sliding member of the seat-frame, and the rear ends of said links are provided with T-shaped heads 40, which are fitted in slots 41, provided in longitudinal rails forming a part of the frame of the back 34. Wear- 90 plates 42 are fastened to the back-rails, and said wear-plates have longitudinal slots which are coincident with the slots in the back-rails. Said links are also provided with laterally-extending lugs 43, arranged to bear 95 against the wear-plates 42 and to assist in sustaining the back when it is lowered to its horizontal position to form one of the seats of the stool. The central bridge-bar 33 of the base member of the frame is provided in 100 its opposite edges with diagonal grooves or channels 44, the edges of which form the inclines or cams 45 and 46, and the upwardly-curved front ends of the links 37 have laterally-extending lugs 37^a, which are arranged 105 to ride against the cams 45 and 46 in the adjustment of the links to raise and lower the back and to project the sliding member of the seat-frame.

The sliding member of the seat-frame is 110 normally retracted, and the back is held in its raised position by means of a strong coiled spring 47, arranged in a horizontal longitudinal position below the seat-frame and to one side of the standard 6, the rear end of 115 said coiled spring being attached in a suitable manner to the base member 31, while the front end of said spring is attached to the hanger 48, fastened on the front cross-rail of the sliding member 32 of said seat-frame. 120 To hold the seat-frame and back in their adjusted positions, I provide two spring-catches 48^a 49, spaced at suitable intervals on and attached to one of the side rails of the sliding member of the seat-frame, and these spring-catches 48^a and 49 have spring-controlled bolts which are normally forced below the sliding member of the seat-frame, and each catch is adapted to engage with a keeper-plate 50, fastened to the front cross-rail of the 125 base member of the seat-frame. The catch 49 is positioned at the front of the sliding member 32 to engage with the keeper-plate when the back is raised and the sliding seat- 130

frame member retracted; but when the back is lowered and the seat-frame member extended the catch 48^a engages with the keeper-plate to hold the parts in said adjusted position. A releasing device 51 is provided on the lower side of the base member of said seat-frame, and said releasing device has a pintle or stud adapted to be lifted by hand and to engage with either of the catches 48^a or 49 for the purpose of freeing either catch from the keeper-plate and to permit the sliding seat-frame member and the back to be adjusted as may be required.

The seat 55 is mounted upon the sliding member 32 of the seat-frame, so as to be carried therewith in its horizontal adjustment and to be capable of a limited vertical adjustment with relation to said seat-frame. On the inside of the seat is provided a series 20 of angularly-slotted plates 56, and these plates are fastened securely within the seat near the corners thereof. Within this seat is arranged parallel rails 57, which are fastened in a suitable way to the frame of the sliding member 32 of the seat-frame, and said rails are provided with slotted keepers 58, which lie adjacent to the angularly-slotted plates 56 on the seat. A seat-lock 59 is arranged within the seat 55 to pass through the slotted 30 guide-plates 58 and engage with the angular slotted plates 56 on the seat. As shown in the drawings, this seat-lock consists of a central stem 59^a and two cross-bars 59^b, attached to the central stem. These cross-bars of the seat-lock pass through the slotted plates 58 and fit in the angular slots of the seat-plates 56, and one end of the central stem 59^a is extended through an aperture 60 in the front rail of the sliding member 32 of the seat-frame, said extended end of the stem being provided with a finger-knob 61 and with a coiled spring 62, said spring being seated at one end against the collar 61^a and at its other end against the front rail of the sliding member of the seat-frame.

The tendency of the spring 62 is to draw the seat-lock into one or the other of the angular offsets in the plates 56; but the seat-lock may be moved longitudinally within the slotted plates 58 for the purpose of bringing the cross-bars 59^b into the vertical members of the slots in said plates 56, thus releasing the seat 55 from locked engagement with the seat-lock 59 and permitting the seat 55 to be raised to its elevated position by the action of the coiled lifting-springs 63, said springs being attached at their upper ends to the seat 55 and fastened at their lower ends to the frame of the slidable member 32 of the seat-frame. When the seat-lock is adjusted to have its cross-bars fit in the upper offsets of the angular slots in the plates 56, the seat 55 is held in a depressed locked position on the seat-frame; but the operator may move the seat-lock longitudinally, so as to bring the ends of the cross-bars 59^b in the vertical parts of the slots in said plates 56, which adjust-

ment of the seat-lock permits the springs 63 to raise the seat above the seat-frame, after which the seat-lock may be shoved back, so 70 that its cross-bars 59^b will enter the lower offsets in the annular slots of said plates 56, thereby locking the seat 55 in its raised position. To lower the seat 55, it is necessary to again adjust the seat-lock, press downwardly 75 upon the seat 55 to place its springs under tension, and move the plates 56 so as to bring the upper offsets in the angular slots thereof in line with the ends of the seat-lock, after which said lock may be pressed back to move 80 its cross-bars into the upper offsets of the angular slots in said plates 56, thereby locking the seat 55 in its lowered or depressed position. The rails 57 and the slotted plates 58 serve to sustain the said lock in operative relation to the seat-frame and to the seat, and said slotted keepers 58 permit of the proper endwise adjustment of the seat-lock to enable the seat 55 to be adjusted vertically, as may be required.

The operation of our improved chair will be described as follows: To raise or lower the chair or stool, the operator moves the adjusting-lever 21 to bring its prong 22 into engagement with the adjusting-ratchet and 95 turn levers 9 to retract the pawls 8 from engagement with the serrated plates 26, after which the standard and seat may be raised or lowered vertically. The seat with the attached back may be rotated freely in a horizontal plane on the standard and the spindle. With the sliding member of the frame retracted and the back in a raised position the structure is adapted to service as a chair to support the back of the operator occupying the 100 chair, and the seat and back are held firmly in place by the strong coiled spring by one or the other of the locking devices 48 or 49 and by the links. To convert the structure into a stool with two seats, the locking device 49 is 105 released and the operator presses backwardly and downwardly on the back 34 and pulls outwardly on the front end of the sliding member of the seat-frame, whereby the links 37 are caused to slide in the channels or grooves 110 44, and the lugs 37^a on said links ride upon the cams 45 and 46 on the central bridge-bar of the base member of said seat-frame, thereby guiding the links in their travel during the lowering or raising of the back 34. The back 115 34 is adapted to be lowered into a horizontal position substantially flush with the seat-frame 30, and during the lowering adjustment of the back the seat-frame member 32 is extended to project beyond the base member 31, and the spring is extended and put under increased tension, said parts being held in their lowered and extended positions by the engagement of the catch 48^a with the keeper-plate. The structure thus forms a 120 stool provided with two seats, the seat 55 being carried by the extensible member of the seat-frame and the back 34 forming the other seat of the stool. In case the structure

is to be used by two persons of different heights the seat 55 may be released by adjusting the seat-lock 59 and permitting the spring 63 to raise the seat to its elevated position, after which the seat-lock is engaged with the angular slotted plates 56 to hold the seat steadily in place. To restore the parts to their positions for service as a chair, the seat 55 is forced down and locked in compact relation to the seat-frame, the catch 48^a is released, and the spring pulls the sliding member of the seat-frame inwardly, and the links raise the back to its normal position substantially at right angles to the seat-frame.

The members of the seat-frame 31 32 are slidably connected together and held in their proper positions by means of long plates 32^b and headed studs or bolts 32^a. (Shown by Fig. 9.) The member 32 of the seat-frame has a longitudinal groove over which is secured the slotted plate 32^b, and to the member 31 of the seat-frame is attached the headed bolt or stud 32^a, which passes through the slot in the plate to have its head occupy the groove in the seat-frame member 32, as shown.

We are aware that changes in the form and proportion of parts and in the details of construction may be made without departing from the spirit or sacrificing the advantages of our invention.

Having thus described the invention, what we claim is—

1. In a convertible chair and stool, the combination of an extensible seat-frame, a back hinged to one member of the seat-frame, and means operatively connecting the hinged back to said extensible seat-frame, substantially as and for the purposes described.

2. In a convertible chair and stool, a sectional seat-frame consisting of a base member and an extensible member slidably fitted thereto, in combination with a back adjustably attached to the extensible seat-frame, and operative connections between said adjustable back and sliding seat-frame member to sustain the back in its lowered position, substantially as and for the purposes described.

3. In a convertible chair and stool, the sectional seat-frame consisting of a base member and an extensible member slidably fitted thereto, in combination with a back hinged to the extensible seat-frame, links operatively connected to the sliding seat-frame member and to the extensible back, and an attaching-spring attached to the respective members of the seat-frame, substantially as and for the purposes described.

4. In a convertible chair and stool, a sectional seat-frame consisting of a base member provided with inclines or cams and an extensible member slidably fitted to the base member, in combination with an adjustable back hinged to the sliding member of the seat-frame, and links slidably attached to the adjustable back, connected with the sliding

member of the seat-frame and provided with projections arranged to ride against the cams of the base member of the seat-frame in raising or lowering the back and extending or retracting the extensible member of the seat-frame, substantially as and for the purposes described.

5. In a convertible chair and stool, a sectional seat-frame consisting of a base member and an extensible member slidably connected thereto, and locking devices for holding the extensible seat member in its retracted or projected positions, in combination with an adjustable back, and operative connections between said adjustable back and the seat-frame, substantially as and for the purposes described.

6. In a convertible chair and stool, the combination of a sectional extensible seat-frame, an adjustable back, means for sustaining said back in either its raised or lowered positions, and a vertically-adjustable seat carried by one member of said sectional seat-frame, substantially as and for the purposes described.

7. In a convertible chair and stool, the combination of a sectional seat-frame having one member thereof slidably connected to the other member, a vertically-adjustable seat carried by said extensible member of the seat-frame, means for locking said seat in its raised or lowered positions with relation to the seat-frame, an adjustable back, and means for sustaining said adjustable back in either its raised or lowered positions, substantially as and for the purposes set forth.

8. The combination with a seat-frame and a vertically-movable seat, of the angularly-slotted plates carried by said seat and provided with offsets at right angles to vertical slots in said plates, rails attached to the seat-frame and provided with slotted keepers, a seat-lock having bars fitted in the slotted keepers and engaging with the angularly-slotted plates, lifting-springs for raising the seat, and a holding device for the seat-lock, substantially as and for the purposes described.

9. The combination with a seat-frame and a vertically-adjustable seat thereon, of fixed rails on the seat-frame, slotted keepers carried by said fixed rails, angularly-slotted plates rigidly attached to the vertically-adjustable seat, a seat-lock having its cross-bars fitted in the keepers and the angularly-slotted plates and provided with a stem which protrudes beyond the seat-frame, and a spring to hold the seat-lock in engagement with the offsets of the angularly-slotted plates, substantially as and for the purposes described.

10. In a convertible chair and stool, the combination with a standard, of a two-part seat-frame having one member mounted on the standard and its other member slidably fitted to said first-named member, a seat-back mounted for adjustment to lie in substantially the horizontal plane of the seat-frame, means for locking the sliding seat-frame in fixed re-

lation to the base member of the seat-frame, and means for sustaining the adjustable seat-back in its horizontal or upright positions, substantially as and for the purposes described.

5 11. In a convertible chair and stool, the combination of a standard, a two-part seat-frame, a hinged back, operative connections between the hinged back and one member of 10 the seat-frame, and a vertically-adjustable seat mounted on the member of the seat-frame to which the hinged back is connected, substantially as described.

12. The combination with a base, of a seat-carrying standard provided with longitudinal channels, pivoted pawls within the channels, levers mounted on the standard within other channels thereof, a toothed adjuster connected loosely with said levers, and an adjusting-lever normally free from the toothed adjuster and adapted to engage therewith to turn the latter and move said levers to retract the pawls, substantially as and for the purposes described.

13. The combination with a base provided 15 with holding-plates, of an angular non-rotatable standard fitted for vertical adjustment within said base, holding-pawls pivoted to the standard and arranged to engage with said holding-plates of the base, vertical levers fulcrumed to the standard and pivoted to said holding-pawls, a toothed adjuster loosely mounted on the standard and having pivotal connections with said levers, and a spring-controlled adjusting-lever arranged to be normally free from engagement with the toothed adjuster and having a prong which may be thrown into engagement with said adjuster, for the purposes described substantially as 30 35 40

14. The combination with a base having a lifting-spring and toothed holding-plates, of a seat-frame, a non-rotatable vertically-adjustable standard fitted in said base, a spindle passing through the standard and pivoted 45

to the seat-frame, a casting having a clip attached to said standard and forming a bearing for the seat-frame, holding-pawls mounted on the standard to engage with the holding-plates of the base, an adjuster also mounted 50 on the standard and on the spindle, levers operatively connected with said adjuster and with the holding-pawls, and an adjusting-lever carried by the seat-frame and arranged to engage with said pawl-adjuster, substantially as and for the purposes described. 55

15. The combination with a seat-frame, of a vertically-adjustable seat, the plates having the vertical slots thereof provided with offsets and carried by the seat-frame, a seat-lock 60 independent of the seat proper and slidingly confined on the seat-frame to normally lie in the horizontal plane thereof and engaging with said angularly-slotted plates to sustain the seat in its raised or lowered position, and 65 a holding-spring fitted against the seat-lock and the seat-frame, substantially as and for the purposes described.

16. The combination with a chambered base, and a vertically-adjustable seat-carrying standard, of the ratchet-teeth disposed in the base on opposite sides of the standard, the oppositely-acting pawls fitted on the standard to engage with the ratchet-teeth, the levers arranged longitudinally of the standard, fulcrumed thereto, and connected at their lower ends to the pawls, a pawl-adjuster pivoted on the standard and connected to the pawl-adjusting levers, and means for actuating said pawl-adjuster, substantially as described. 70 75 80

In testimony that we claim the foregoing as our own we have hereto affixed our signatures in the presence of two witnesses.
